COLLAPSIBLE ENCLOSURE FOR LAVATORIES OR THE LIKE

Philip A. De Lucia, 57 Lincoln Ave.,
Cliffside Park, N.J. 07010

Filed Dec. 20, 1974, Ser. No. 534,769

Term of patent 14 years

Int. Cl. D23—02

U.S. Cl. D6—181

FIG. 1

FIG. 2

FIG. 3

FIG. 4

FIG. 5

FIG. 6

FIG. 7

FIG. 8

FIG. 1 is a front perspective view of the collapsible lavatory enclosure of my design, fully assembled.

FIG. 2 is a rear perspective view of the enclosure of my design with the top removed.

FIGS. 3, 4 and 5 show progressive steps in folding the collapsible enclosure of my design.

FIG. 6 shows the collapsible enclosure of my design, completely closed.

FIG. 7 shows the rear perspective view of the collapsible enclosure of my design, completely folded together with the disassembled top in position for shipment or storage.

FIG. 8 is the front perspective view of the collapsible assemblage of FIG. 7, completely collapsed.

I claim:

The ornamental design for a collapsible enclosure for lavatories or the like, as shown.
